UNITED STATES PATENT OFFICE.

GEORGE F. McINDOE AND JAMES W. McINDOE, OF BOSTON, MASSACHUSETTS.

IMPRESSING LETTERS AND MARKS ON CIGARS.

SPECIFICATION forming part of Letters Patent No. 379,020, dated March 6, 1888.

Application filed January 31, 1887. Serial No. 226,001. (No model.)

To all whom it may concern:

Be it known that we, GEORGE F. MCINDOE and JAMES W. MCINDOE, both of Boston, in the county of Suffolk and State of Massachusetts, both citizens of the United States, have invented a new and useful Improvement in Processes of Impressing Letters, Marks, &c., on Cigars, of which the following is a full, clear, and exact description, reference being had to the accompanying drawings, forming a part of this specification, in explaining its nature.

The invention relates to the process of impressing letters, figures, designs, and trade or other marks on cigars, which involves the tempering of the cigar or other wrapper by moisture and impressing in the cigar while in temper the said letters, &c., by impression devices which comprise an impression die or mold in relief and a support for the cigar of a character to hold it upon all sides excepting the side exposed to the impression die or mold and during the movement of one in relation to the other to cause the die or mold to enter the substance of the cigar.

We have ascertained that in order to form in cigars letters or marks of any kind in a practical way the cigar cannot be treated while in its ordinary dry state, but that it must be moist while being thus treated, or, in other words, while being subjected to the pressure necessary in forming by a relief-die the sunken letters or marks therein. This temper is especially necessary in the wrapper of the cigar, but not essential to the filling, although it is desirable that that also should be in the same temper. This temper is provided either by taking the cigar immediately after it has left the maker's hands and while the wrapper is in the temper which is necessary for the proper handling of the same in the operation of making the cigar, or by subjecting the completed cigar to the influence of damp atmosphere or to a slight spray, or by moistening it in any other way, and the cigar while in this state is subjected to the action of the impressing devices, and considerable pressure can then be applied to it without rupturing or fracturing the wrapper.

In the drawings, Figure 1 is a view illustrating our form of appliance for tempering the

cigars. Figs. 2 and 3 illustrate the impressing devices. Fig. 4 is a view of a cigar with letters impressed in its substance. Fig. 5 is a section upon the line *xx* of Fig. 4.

We have shown in the drawings, for impressing the letters, marks, &c., in the cigar, a plate bearing the relief die or mold *A* and a cigar-holding device, *B*, and the mold is adapted to have a movement toward and from the opening to the cigar-holding device. We would say, however, that we do not confine ourselves to this especial form of device for impressing the letters, marks, &c., in the cigar, but may use any other suitable device for practicing this step of the process adapted to form letters, marks, &c., in the substance of the cigar by pressure.

In tempering the cigar care should be taken not to make it too wet, or, in other words, the cigar should not absorb too much moisture.

Any suitable appliance may be used for tempering the cigars, and we would mention, among others, spraying water upon them by an atomizer, placing the same between layers of damp cloth or cotton; but we do not confine ourselves to any especial means for obtaining this result, as there are many methods which can be used which are substantially the equivalents of those mentioned.

In Fig. 1 we have shown a device for tempering the cigars embracing a support or bed, *a*, an endless porous belt, *b*, arranged above the bed and supported by rolls *b'*, and adapted to receive moisture from a tank, *b²*, or any other source of supply and to apply it to the cigars placed between its under surface and the bed by the movement of the belt, which also causes the cigars to be revolved, so that all surfaces of each cigar are brought into contact with the belt as they are moved through the device.

In some instances it will be desirable to heat the relief-die, so that certain letters are impressed by the action of the heated die or mold.

By this process we are enabled to make darker letters or marks or letters or marks that contrast with the wrapper of the cigar. This arises from the fact that the tempering of the cigar or wrapper causes it for the time being to be made darker, and that

while the cigar is in this dark or tempered condition the letters are formed by the dies, which are heated, and this causes the letters or marks thus formed in the substance of the 5 cigar to remain dark, while the wrapper, upon the drying of the cigar, assumes its original or lighter color; and this is of material consequence, in that it causes the letters or marks to show or stand out more prominently 10 and clearly by the contrast.

Having thus fully described our invention, we claim and desire to secure by Letters Patent of the United States—

1. The process of impressing letters, figures, 15 designs, trade or other marks, &c., in cigars, consisting in tempering the cigar or its wrap-

per by moisture, and then while in this moist condition subjecting it to the action of devices for impressing the letters, figures, &c., therein, substantially as described.

2. The process of impressing letters, figures, 20 designs, trade or other marks, &c., in cigars, consisting in tempering the cigar or its wrapper by moisture, and then while in this moist condition subjecting it to the action of a heated relief or impression die, substantially as de- 25 scribed.

GEORGE F. McINDOE.
JAMES W. McINDOE.
